CIRCULAR WINDOW CONSTRUCTION

Oliver M. Edwards, Syracuse, N. Y., assignor to
The O. M. Edwards Company Inc., Syracuse,
N. Y., a corporation of New York

Application April 2, 1937, Serial No. 134,639
Renewed July 15, 1939

8 Claims. (Cl. 189—64)

- This invention relates to circular window constructions, and has for its general object a circular window construction, which is extremely simple and economical in manufacture, highly efficient and durable in use, and which may be sold at such a low price that it is practical for use in such vehicles, as trailers, and in other situations, where a low priced, high-class window is imperative.
- It further has for its object a circular window construction including a circular window frame and a circular discoidal sash rotatably mounted in the window frame and composed of two semi-circular or semi-discoidal sections of different character, as one with a glass pane and the other with a screen, with the glass section normally exposed in a semi-circular window opening in the body of the vehicle, and the other section located in a well in the vehicle body, with the sash rotatable in the window frame to shift the entire sash to carry one section wholly or partly into the well and the other section wholly or partly into the semi-circular window opening.
- It further has for its object a circular window frame—for such a sash in which one half of the frame extends into a well—having a semi-annular flange and a diametrically extending flange forming a facing for the semi-annular margin of the wall around the window opening and a sill piece extending along the base of the semi-circle of said opening.

The invention consists in the novel features and in the combinations and constructions hereinafter set forth and claimed.

In describing this invention, reference is had to the accompanying drawings in which like characters designate corresponding parts in all the views.

Figure 1 is an elevation, partly broken away, of this circular window construction, the contiguous portion of the vehicle body being also shown.

Figure 2 is an enlarged sectional view on line 2—2, Figure 1.

Figure 3 is a sectional view of the window frame taken approximately on line 2—2, Figure 1.

Figure 4 is a fragmentary elevation, partly broken away, looking to the left in Figure 3.

Figure 5 is a fragmentary elevation of the sash, looking to the left in Figure 2, and illustrating particularly the finger pieces for operating the sash.

Figure 6 is a fragmentary elevation, similar

to Figure 1, of a slightly different form of the invention.

Figure 7 is a sectional view on line 7—7 Figure 6.

Figure 8 is a sectional view on line 8—8 Figure 6.

Figure 9 is a fragmentary elevation of two separate semi-circular sashes of Figure 6 assembled together.

1 designates the framing of the body of the vehicle, as for instance a trailer, and 2, 3 the inner and outer walls of the body, which are secured to the framing 1. The body is formed with a semi-circular window opening 4 and with a well 5 at one side, as below the opening. The 15 body is also formed with a frame member 6 extending along the base of the semi-circular opening. The semi-circular opening is usually arranged with its base line extending horizontally and with the well below the window opening. 20

7 designates the circular window frame which includes a body 8 fitting in the semi-circular wall of the window opening 4 and extending into the well 5. The body 8 is formed with a sash 25 guide, here illustrated as an inwardly extending annular rib 9. The body is also formed with a semi-annular flange 10 arranged at a right angle to the body 8 and forming a facing for the semi-annular margin of the wall 2 around 30 the window opening 4, and also with a diametrically extending horizontal sill facing flange at 11. The flange 10 also extends inwardly at 12 parallel to the rib 9. The half of the window frame which extends into the well 5 is unprovided with a facing flange 10. The frame 7 is secured in the window opening by fastening members, as screws, extending through the flange 10 in the framing 1. 35

13 designates the sash as a whole, this being composed of semi-circular or semi-discoidal sections 14, 15 of different character, one section being here shown as having a glass pane or panel and the other a screen panel. The circular sash frame 13 has a diametrically extending rail or 45 bar 16 which separates the glass section from the screen section. The section 14 and the bar 16 is formed with a re-entrant groove 17 for receiving the margin of the glass pane, a suitable glazing strip 18 being located in the groove. The 50 lower section 15 of the frame of the sash 13 and also the bar 16 is formed with a recess 19, angular in cross section, for receiving the margin of the screening, the margin being clamped in the recess 18 in any suitable manner, as by glazing 55

strips 21. The sash is formed with a peripheral groove 20 for receiving the guide rib 9, a suitable non-metal U-shaped weather and wear strip 20^a being located in the groove.

5 One side of the re-entrant groove 17 and the side of the angular recess 18 is here shown as removable, this removable side being preferably a flat annular ring 22 having a diametrically extending rib 23. The ring 22 and rib 23 are 10 secured respectively to the circular portion of the sash frame and to the bar 16, as by screws 24. This is primarily for the purpose of facilitating the mounting of the sash in the window frame with the rib 9 in the peripheral groove 20 15 of the sash frame. It also serves to facilitate re-glazing and for renewing the screen. Preferably, a weather strip 25 is carried by the transverse sill-facing flange 11 of the window frame, this coacting with the diametrically extending 20 bar 16 or the removable side 23 thereof, particularly when the sash is in normal position or when the glass section entirely closes the window opening.

A suitable handle or handles may be provided for turning the window sash in the window opening, these being located preferably near the peripheral edge of the sash, and as here shown, the window frame is provided with webs 26 in the corners formed by the transverse member or bar 30 16, where it meets or joins the circular sash frame, these webs being formed with finger openings 27. By reason of the webs, the openings 27 on the glass side of the bar 16 may enter the entrance of the well, when the window is fully opened, 35 and the screen brought fully into the window opening, and likewise the openings 27 on the screen side of the sash will then be in position to again rotate the circular frame, so that the sash may be rotated to again bring the glass into 40 position to fully close the window opening and locate the screen entirely below the well.

In assembling the window frame in the body of the vehicle, with or without the sash in the window frame, the window frame is lifted and 45 tilted out of the vertical slightly, so that the lower screen section thereof can be inserted in the well, and then the upper end of the screen swung inwardly into the window opening and secured thereto.

50 In Figure 7, 31 designates the framing of the body of the vehicle, and 32, 33 the inner and outer walls or facings of the body which are secured to the framing 31. The body is formed with a semi-circular window opening, as in Figure 1, and 55 with a well at one side of the opening. The body is also formed with a transverse frame member 36 extending along the base of the semi-circular opening. The semi-circular opening is usually arranged with its base line extending horizontally 60 and with the well below the opening.

37 designates the circular window frame, which includes a body fitting into the semi-circular window opening and also extending into the well below the opening, the body having the facing 65 flanges, corresponding to the flanges 10, 12 (Figures 1, 2 and 3).

The window frame (Figure 6) is for the most part of the same construction as that shown in Figures 1 and 2, with the exception that the circular window frame is a split ring cut transversely at S and capable of being expanded slightly, and with the further exception that the diametrically extending horizontal sill facing flange 41, corresponding to the flange 11 (Figure 1), is demountable for the purpose of permitting the expansion

of the window frame. It is here shown as secured at its ends to the window frame by screws 42 and also secured to the vehicle body or the framing thereof, as by screws 43. The screws 42 pass through the ends of the facing flange 41 5 and into the window frame and the screws 43 pass through the flange 41 into the frame in the wall structure of the vehicle around the window opening. The sill facing 41 is provided with an angular flange 44 which overhangs the sill 10 and coacts with a weather strip 45 on the sash to be presently described.

46 and 47 designate respectively upper and lower semi-circular sash frame sections, one carrying a glass pane and the other a screen. These 15 sections are separate units instead of one integral unit, as in Figures 1 and 2, and each is provided with a diametrically extending rail 48 or 49. The rails abut edgewise against each other and are 20 detachably secured together.

As seen in Figure 7, one of the rails, as the rail 48, is formed with a lengthwise groove 50 for receiving a tongue 51 on the other rail 49, and these two rails are formed with a recess 52 between them in which is interlocked the base 25 53 of the weather strip 45. When assembled, the upper and lower semi-circular sash sections are rigidly secured together by screws 54, extending transversely through the rail 48 and the tongue 51 of the rail 49. The margin of the 30 screen 55 is clamped between a binding strip 20 and the rail 49 and by similar binding strips to the circular portion of the lower sash frame 47. The binding strips are secured in position by screws 62.

63 designates a handle secured to one end of the rail 49. This handle is double or U-shaped and is located above the sill. When the sash is to be turned in the window frame, to move the upper sash section with the glass pane into open 40 position, lifting force is applied to the uppermost branch 63 of the U formation, and when the glass section is entirely open, this particular branch 63 will lie against the sill. To again close the glass section and move the screen section 45 back into the well, the other branch of the U formation, which is now uppermost, is utilized, and this branch will lie against the sill, when the glass section is entirely closed, and the screen section entirely in the well. The handle 63 is 50 held in position by two of the screws 54, which, as before described, secure the upper and lower semi-circular sections together and extend transversely into the rail 48.

The upper and lower sash sections are first 55 assembled together, as a unit, and this unit mounted in the window frame by expanding the circular window frame slightly or enough to permit the two semi-circular sash sections assembled to be fitted into the sash guides. The window 60 frame is then contracted, and before being inserted in the window opening, the sill facing 41 is secured in position by means of the screws 42. The sill facing holds the circular window frame in contracted position. The window frame is 65 then placed in the window opening in the manner described in connection with the construction shown in Figures 1 and 2. The window frame is secured in position by the screws 43 and also additional screws 43^a.

70 What I claim is:

1. In a window construction, a circular frame formed with a sash guide, a sash rotatably mounted at its peripheral edge in the window frame and comprising opposite semi-circular sections of dif- 75

ferent character, in combination with a body frame having a semi-circular window opening, and a well opening through the base side of the semi-circular window opening for receiving one of the semi-circular sections, the sash frame being supported solely at its periphery and being rotatable within the window frame to bring either section partly or wholly into the semi-circular opening and the other section partly or wholly into the well.

2. In a window construction, a circular frame comprising a circular body formed with a sash guide and one half thereof being formed with a semi-annular flange at an angle to the body and with a diametrically extending flange between the ends of the former flange, said flanges providing a facing for a semi-circular window opening, and a transverse sill, a sash rotatably mounted at its peripheral edge in the body and being supported in the body entirely at its peripheral edge, the sash comprising opposite semi-discoidal sections of different character, in combination with a body formed with a semi-circular window opening, and a well opening into the window opening through the base of the semi-circular window opening, the portion of the body located in the well being unprovided with a facing flange.

3. The combination with a vehicle body formed with a semi-circular window opening and with a well at one side of the window opening and opening thereinto along the base of the semi-circle of said opening, of a circular window frame including a body mounted in the window opening and extending into the well and having a semi-annular flange and a transverse diametrically extending flange forming a facing for the margin of the vehicle body around the semi-circular window opening, a circular sash rotatably mounted in the body of the frame and supported therein entirely at the peripheral edge of the sash, the sash comprising semi-discoidal sections of different character, the sash being rotatable in the window frame to shift either section partly or wholly into the well and the other section partly or wholly into the window opening.

4. In a window construction, a circular window frame divided at one side thereof, whereby it is expandable and contractile, the frame being formed with a sash guide, a frame member extending diametrically of the circular frame and being detachably secured at least at one end to the circular frame to permit expansion and contraction of the circular frame, when detached,

a sash rotatably mounted at its peripheral edge in the frame and supported therein entirely at its peripheral edge, in combination with a body formed with a semi-circular window opening, and a well opening into the window opening through the base of the semi-circular window opening.

5. In a window construction, a circular frame comprising a circular body formed with a sash guide, a sash rotatably mounted at its peripheral edge in the frame and supported entirely at its peripheral edge, the sash comprising separate semi-discoidal sections of different character arranged in the same plane, each section having a transverse diametrically-extending rail, the rails abutting edgewise against each other.

6. In a window construction, a circular frame comprising a circular body formed with a sash guide, a sash rotatably mounted at its peripheral edge in the frame and supported entirely at its peripheral edge, the sash comprising separate semi-discoidal sections of different character arranged in the same plane, each section having a transverse diametrically-extending rail, the rails abutting edgewise against each other, one rail being formed with a groove and the other with a tongue interfitting in the groove.

7. In a window construction, a circular frame comprising a circular body formed with a sash guide, a sash rotatably mounted at its peripheral edge in the frame and supported entirely at its peripheral edge, the sash comprising separate semi-discoidal sections of different character arranged in the same plane, each section having a transverse diametrically-extending rail, the rails abutting edgewise against each other, one rail being formed with a groove and the other with a tongue interfitting in the groove, and fastening means extending transversely of the rails and through said tongue.

8. In a window construction, a circular frame comprising a circular body formed with a sash guide, a sash rotatably mounted at its peripheral edge in the frame and supported entirely at its peripheral edge, the sash comprising separate semi-discoidal sections of different character arranged in the same plane, each section having a transverse diametrically-extending rail, the rails abutting edgewise against each other, a weather strip having a base portion clamped between the rails, the frame having a diametrically-extending sill facing provided with a flange coaction with said weather strip.

OLIVER M. EDWARDS.
